FLOWER POT

Frank Luipersbek, Bronx, N. Y.

Application August 28, 1956, Serial No. 42,750

Term of patent 14 years

(Cl. D35—3)

FIG. 2-

FIG. 4-

Fig. 1 is a perspective view of a flower pot, showing my new design;

Fig. 2 is a transverse cross-sectional view taken on line 2—2 of Fig. 1;

Fig. 3 is a fragmentary longitudinal cross-sectional view on a slightly reduced scale taken on line 3—3 of Fig. 1; and

Fig. 4 is a side elevational view of Fig. 1 on a reduced scale.

I claim:

The ornamental design for a flower pot, as shown.
